UNITED STATES PATENT OFFICE.

FERNAND HOLWECK, OF PARIS, FRANCE, ASSIGNOR TO THE MULLARD RADIO VALVE COMPANY, LIMITED, OF LONDON, ENGLAND.

VACUUM PUMP.

Application filed May 11, 1922. Serial No. 560,165.

To all whom it may concern:

Be it known that I, FERNAND HOLWECK, a citizen of the French Republic, residing in Paris, France, have invented certain new and useful Improvements in Vacuum Pumps, of which the following is a specification.

This invention is for improvements in or relating to vacuum pumps for producing 10 very high vacua, of the type introduced by Gaede and known as molecular pumps.

Gaede has proposed (see Annalen der Physik, vol. 41, p. 337) to use a cylindrical rotor mounted in a cylindrical stator which 15 is provided on its internal surface with a spiral groove, the direction of rotation of the rotor being such that the gas which is being evacuated is caused to travel longitudinally of the pump along this groove to the outlet which communicates with the auxiliary vacuum pump. The present invention has for its object to provide an improved construction of pump provided with such a spiral groove extending from the inlet to the outlet, whereby the efficiency is improved and the rate at which the required degree of 20 vacuum can be produced is considerably increased.

According to this invention, a vacuum pump of the type described and formed with a spiral groove on one of the opposed faces of the stator and rotor extending from the inlet to the outlet, is characterised in that the cross-sectional area of the said groove diminishes progressively in passing along it from the inlet to the outlet.

According to another feature of this invention, the pump is constructed of cylindrical form having a cylindrical stator provided with an inlet intermediate of its ends, and with two spiral grooves of opposite pitch extending in opposite directions from the inlet towards the ends of the pump.

In a modified construction of pump according to this invention, it may comprise a flat cylindrical stator casing and a disc-shaped rotor within it, and the tapered spiral groove or grooves are formed on any or all of the opposed inner faces of the 50 stator and rotor.

According to another feature of this invention, the driving of the rotor of a vacuum pump as above described is effected by means of a magnetic rotor enclosed in the stator, or in an air-tight casing in commun-

cation with the interior of the stator, together with external means for imparting a drive magnetically to the said magnetic rotor.

In the accompanying drawings, which illustrate more or less diagrammatically some embodiments of this invention—

Figure 1 is a central longitudinal section of a cylindrical pump;

Figure 2 is an elevation in section on the line 2—2 of Figure 1;

Figure 3 is a central section of a flat disc-shaped pump, and

Figure 4 is a face view of the stator-casing, taken on the line 4—4 of Figure 3.

Like reference characters indicate like parts throughout these drawings.

Referring first to Figures 1 and 2, the pump comprises a hollow cylindrical stator-casing 10 closed at its ends by means of 75 end plates 11. A pipe connection 12 communicates with the interior of the stator at the middle of its length, and constitutes the connection whereby the vessel to be evacuated is connected to the pump, that is to say, the pipe 12 constitutes the inlet to the 80 pump.

The curved internal surface of the stator is provided with two spiral grooves formed on it; these grooves are of opposite pitch, 85 and they extend from the inlet pipe 12 to the ends of the stator. As illustrated these grooves are of substantially rectangular section, and an important feature according to this invention is that the cross-sectional area 90 of each of the grooves diminishes progressively from the inlet end of the groove to the outlet end. This diminution in cross-section can be effected in various ways, as for example by diminishing the width, or the 95 depth, or both of these dimensions. Obviously the grooves need not be of rectangular cross-section, but they can be curved, semi-circular, oval or of any other shape

which is convenient in manufacture. The 100 only requisite is that the spiral ridge 14 forming the wall between adjacent convolutions should have its face opposite the rotor suitably situated with respect to the rotor to enable the pump to operate in the well 105 known manner; that is to say there must be only a small clearance, say of the order of .01 to .05 millimetres. The invention is not limited, however, to these particular dimensions, since any other suitable dimensions 110

may be used. The two ends of the stator-casing communicate with the outlet from this pump which is indicated at 15 in Figure 2, the pipe 15 opening into a channel 16 5 extending longitudinally of the stator and communicating with the interior thereof at the two ends.

The rotor consists of a plain cylindrical member 17 mounted on a shaft 18 which is 10 rotatable in ball-bearings 19 in the end plates 11 of the stator-casing. One of the bearings, 19, is provided with a closed cover 20 which forms an air-tight joint, and the other bearing is provided with a suitably 15 packed bushing 21 which provides an air-tight joint for a driving connection 22, whereby a drive is imparted to the shaft 18 and the rotor. The bush 21 may be packed with thick grease or other material, for 20 the purpose of making a tight joint with the member 22.

In the modified construction illustrated in Figures 3 and 4, the stator-casing 23 is of flat cylindrical form and a flat spiral groove 24 is formed on one of its internal faces. One end of the groove communicates with the inlet 25, and the outlet 26 to the auxiliary pump communicates with the other end of the groove. This groove 24 may be of 30 any desired shaping and cross-section, and tapers, so as to get progressively smaller from the inlet to the outlet.

The rotor 27 is in the form of a flat disc carried by a shaft 28 which rotates in ball-bearings 29 in an extension 30 of the stator-casing.

It will be appreciated that the tapered spiral groove or grooves above-mentioned may be formed on either of the opposed 40 faces of the stator and rotor, and in the case of the construction illustrated in Figures 3 and 4, the groove could be formed on both the internal flat faces of the stator, so that both flat faces of the rotor are operative; alternatively, the grooves could be 45 formed on both flat sides of the rotor if so desired.

Figure 3 also illustrates a modified arrangement for driving the rotor, and it is to 50 be understood that this arrangement could also be applied to the construction illustrated in Figure 1.

Referring to Figure 3, the stator-casing 23, 30 is provided at the open end of the 55 part 30 with an air-tight cap 31 within which there is mounted a magnetic armature or rotor 32 which is secured on an extension of the rotor shaft 28 or is otherwise in driving engagement therewith. The 60 casing 31 is of non-magnetic material, and the stator of an asynchronous motor 33 is arranged outside it to cooperate with the

armature or rotor 32 to impart a drive to it magnetically. With this arrangement there is no necessity for the driving shaft of the rotor 27 to extend through the stator-casing, and all difficulties in packing it to make a tight joint are thereby avoided, the stator casing being completely closed except for the inlet and outlet passages 25, 26. 70

It will be seen that in the various constructions of pump hereinbefore described, the rotor is mounted in ball-bearings, which are either within the stator-casing or in free communication therewith, and this is 75 of importance from manufacturing considerations, since bearings of the ball or roller type can be arranged to run either without lubricant or without a continuous or even intermittent supply of lubricant, so that the 80 air-tight construction of the stator-casing is much facilitated, and this is particularly the case when the magnetic drive illustrated in Figure 3 is also used. These constructions of pump can therefore be relied upon for 85 continuous service if so desired.

This invention, therefore, provides a pump which may be designated as commercial apparatus, as distinguished from a laboratory instrument, and furthermore, the 90 invention is held to cover the combination of the improved vacuum pump hereinbefore described with any vessel or apparatus in which it is required to maintain a high degree of vacuum, the pump then being permanently connected to the vessel or apparatus and set in operation when necessary. 95

What I claim as my invention and desire to secure by Letters Patent is:—

1. In a vacuum pump of the character described, the combination of a cylindrical stator and a cylindrical rotor, mounted one in the other, one of which members has an inlet and an outlet and is formed with a spiral groove on its face opposed to the other member extending from the said inlet to the said outlet, the cross-sectional area of which groove diminishes progressively in passing along it from the inlet to the outlet. 105

2. In a vacuum pump of the character described, the combination of a cylindrical stator and a cylindrical rotor mounted one in the other, one of which members has an inlet and two outlets, one on either side of the inlet, and is formed with two spiral grooves of opposite pitch on its face opposed to the other member extending each from the said inlet to one of said outlets, the cross-sectional area of which groove diminishes progressively in passing along it 110 from the inlet to the outlet. 115

In testimony whereof I affix my signature.

FERNAND HOLWECK.
